UNITED STATES PATENT OFFICE.

GEORGE O'NEILL, OF MONCTON, NEW BRUNSWICK, CANADA.

SMOKE-CONSUMER.

1,145,504.

Specification of Letters Patent.

Patented July 6, 1915.

Application filed January 18, 1915. Serial No. 2,870.

To all whom it may concern:

Be it known that I, GEORGE O'NEILL, of 280 High street, in the city of Moncton, in the Province of New Brunswick, Dominion 5 of Canada, have invented certain new and useful Improvements in Smoke-Consumers, of which the following is the specification.

This invention relates to smoke consumers and fuel savers of the type in which a portion of the smoke is returned to the boiler fire box, and the objects of the invention are to provide improved means for collecting a portion of the smoke from the smoke box of the boiler and for mixing it with air 15 and steam and injecting it beneath the fire grate, all as hereinafter more fully set forth and described in the accompanying specification and drawings.

In the drawings, Figure 1 is a transverse 20 sectional view through a steam boiler furnace embodying the present invention. Fig. 2 is a sectional elevation taken at right angles to Fig. 1.

Like characters of reference refer to like 25 parts in the several figures.

Referring to the drawing, A represents a boiler of any suitable type arranged singly or in batteries having suitable fire tubes therein and supported in a suitable masonry 30 structure B.

C represents the fire grate and D the smoke box, both of usual construction.

The smoke consuming device forming the present invention comprises a pair of U-shaped pipes F having horizontal parallel arms 12 and 13, the upper horizontal arms projecting through the masonry structure into the smoke box and being formed with downwardly opening flaring ends 14, the 40 flaring mouths meeting at the center to form a V-shaped deflecting shield 15 which divides the products of combustion between the two mouths. These mouths are located just above the opening of the tubes and extend completely across the front of the smoke box while occupying only part of the width of the same so that a certain percentage of the smoke may pass directly to the stack G. The lower parallel arms of the 50 U-shaped pipes F project through the masonry structure to beneath the grate and

are formed on the outer end with branch connections 17, which branch connections discharge across the vertical portions 18 of the pipes F, the said branch connections 55 having air valves 19 in their outer ends of any suitable type and steam jets 20 extending through the center of the air valve, the said steam jets having suitable controlling valves 21. In the smoke box above the V-shaped shield 15 and protected by the shield from the products of combustion a T-piece 22 is provided, connected to steam jets 23 and 24 which project into the arms 12 and to a supply pipe 25 for live steam. 60

In operation the steam jets 23 and 24 will entrain a portion of the products of combustion and smoke from the smoke box and cause them to pass through the pipes F and discharge through the parallel arms 13, at 70 the same time the jets 20 discharging across the vertical portions 18 will assist in the circulation and will also entrain regulated quantities of air through the valves 19.

As many changes could be made in the above 75 construction and many apparently widely different embodiments of my invention, within the scope of the claim, constructed without departing from the spirit or scope thereof, it is intended that all matter contained 80 in the accompanying specification and drawings shall be interpreted as illustrative and not in a limiting sense.

What I claim as my invention is:

A smoke consumer comprising in combination, a boiler having a fire grate, a smoke box, a supporting masonry structure, U-shaped pipes, the parallel arms of which are horizontally disposed, the upper parallel arms being designed to project through 90 the masonry structure surrounding the boiler and into the upper part of the smoke box, the lower parallel arms of the pipes being designed to project through the masonry structure and beneath the fire grate, 95 branch connections for the lower arms open at the ends, air valves in the outer ends of the branch connections, steam jets extending in the branch connections and discharging across the vertical portion of the U-shaped pipes, flaring mouths formed on the 100 inner ends of the upper parallel arms, said

flaring mouths meeting to form a V-shaped shield which divides the products of combustion, a T-piece located above the V-shaped shield and connected to a supply of steam, and steam jets leading from the T-piece into the upper parallel arms, substantially as described.

In witness whereof I have hereunto set my hand in the presence of two witnesses.

GEORGE O'NEILL.

Witnesses:

JAMES M. KNIGHT,
FRANCIS P. MURPHY.
